UNITED STATES PATENT OFFICE.

HENRY T. MORSE, OF BOSTON, MASSACHUSETTS, ASSIGNOR TO MICHAEL R. GATELY, OF SAME PLACE.

BOOK-CLASP.

SPECIFICATION forming part of Letters Patent No. 247,467, dated September 20, 1881.

Application filed July 30, 1881. (No model.)

To all whom it may concern:

Be it known that I, HENRY T. MORSE, of Boston, in the county of Suffolk and State of Massachusetts, have invented certain Improvements in Book or Album Clasps, of which the following is a specification.

This invention relates to book or photograph-album clasps which are adjustable so that they can be extended to clasp a book or album when the same has been thickened by the insertion of pictures or other objects.

The invention has for its object to provide an improved adjustable or extensible clasp, which shall be simple and inexpensive in construction, convenient in operation, and pleasing in appearance.

To these ends my invention consists in a clasp the hinged or swinging member of which is composed of an arm hinged, as usual, to one lid of the book or album and a plate pivoted to said arm so as to rotate thereon, and provided with orifices at different distances from the pivot, either of said orifices being brought by the rotation of the plate into position to engage with the stud or fixed member of the clasp on the opposite lid, as I will now proceed to describe and claim.

Of the accompanying drawings, forming part of this specification, Figure 1 represents an edge view of an album having a clasp embodying my invention. Fig. 2 represents a section on line $\alpha\alpha$, Fig. 1.

The same letters of reference relate to the same parts in each figure.

In the drawings, a a' represent the lids of an album or other book to be connected by my improved clasp.

b represents the swinging member of the clasp, which is composed of an arm, 1, of any desired shape, hinged to the lid a in the same manner that the swinging member or arm of an ordinary clasp is usually hinged, and a plate, 2, pivoted at p to the arm 1 and projecting beyond the outer end of said arm. The plate 2 is adapted to rotate on the arm 1, and is provided with two or more orifices, e , each located at a different distance from the pivot from the other or others. The plate may be rotated to cause either of its orifices to pro-

ject beyond the arm 1, and enable such orifice to engage with the stud c and to regulate the length of the swinging member of the clasp, the length of said member being determined by the distance between the operating-orifice and the pivot of the plate 2. It will be seen, therefore, that as the distance between each orifice and the pivot varies, the length of the swinging member varies with each change in the position of the plate. The clasp is thus adapted to hold lids more or less widely separated.

The plate 2 may be made of any desired form. I prefer to give it the form of a leaf, as shown in Fig. 1, this form imparting a pleasing and ornamental effect to the clasp. The plate may, however, be made in the form of a star, a butterfly, or in any suitable ornamental shape.

I do not limit myself to the use of orifices in the plate 2 adapted to engage with a stud, for the plate may be provided with hooks arranged at different distances from the pivot and adapted to engage with a suitable eye on the opposite lid without departing from the spirit of my invention.

I prefer to interpose between the arm 1 and plate 2 a washer, w , to prevent the plate from rubbing against and scratching the arm.

Having thus described my invention, I claim—

1. A clasp the swinging member of which is composed of a hinged arm and a plate pivoted thereto, provided with orifices or equivalent devices arranged at different distances from the pivot of the plate and adapted to engage with the other member of the clasp, as set forth.

2. The combination of the arm 1, plate 2, and washer w , as set forth.

In testimony whereof I have signed my name to this specification, in the presence of two subscribing witnesses, this 27th day of July, A. D. 1881.

HENRY T. MORSE.
